Specification for Design.

Patented May 4, 1920.

Application filed September 23, 1919. Serial No. 325,786. Term of patent 3½ years.

To all whom it may concern:

Be it known that I, ANDREW C. WOOD, a citizen of the United States, and a resident of the city of Chicago, in the county of Cook and State of Illinois, have invented a new, original, and ornamental Design for a Searchlight, of which the following is a specification, reference being had to the accompanying drawings, forming a part thereof.

In the drawings:

Figure 1 is a front elevation of a searchlight embodying this design.

Fig. 2 is a rear elevation of the same.

I claim:

The ornamental design for a searchlight as shown.

In testimony whereof, I have hereunto set my hand at Chicago, Illinois, this 16th day of September, 1919.

ANDREW C. WOOD.
